UNITED STATES PATENT OFFICE.

NELSON W. CADY AND CHARLES B. LONGWELL, OF LOGANSPORT, INDIANA.

SPLINT.

1,174,675.

Specification of Letters Patent.

Patented Mar. 7, 1916.

Application filed July 30, 1915. Serial No. 42,769.

To all whom it may concern:

Be it known that we, NELSON W. CADY and CHARLES B. LONGWELL, citizens of the United States, and residing at Logansport, in the county of Cass, State of Indiana, have invented certain new and useful Improvements in Splints; and we do declare the following to be a full, clear, and exact description of the invention, such as will enable others skilled in the art to which it pertains to make and use the same.

Our invention relates to improvements in splints and more especially to a splint for use in the treatment of what is commonly known as "Colles's" fracture and other fractures of the radius and ulna.

The invention consists in the several features and combination of features as more fully hereinafter described and claimed.

20 The object of the invention is to provide a splint one form or size of which will fit and can be applied equally as well to the right or left arm.

A further object is to provide a splint 25 which will embrace and retain in correct adjustment or position the palm of the hand, the head of the radius and the upper part of the forearm.

A further object is to provide a splint 30 which effectually meets the most important indications in the treatment of "Colles's" fracture and other fractures of the forearm by supporting the head of the radius, holding the ulnar styloid in its proper position and at the same time does not in any way obstruct or impede the free circulation of the blood in the affected arm being treated.

A further object is to provide a splint 40 which will hold the parts being treated securely and rigidly and allow them to knit and heal in proper shape, and at the same time prevent any undue pressure on the tissues and give the patient the greatest ease 45 possible.

A still further object is to provide a splint which is simple, inexpensive, durable and light in construction and very convenient and effective in use.

50 Referring to the drawings: Figure 1 is a front view in elevation of our splint showing it as it appears when in use applied to the forearm and hand. Fig. 2 a front view of the splint. Fig. 3 an end view. Fig. 4 55 a top plan view of the frame of the splint with the covering removed.

In the drawings in which like reference characters denote like parts throughout the several views, 1 represents the splint comprising an integrally formed member 2, 60 preferably made of wire, having longitudinally extending strips or rods 3 and 4, which converge from their inner to their outer ends, loops 5 and an obliquely extending hand supporting arch 6 opening at the 65 rear. The arch 6 is secured at the point 7 by means of a wrapping of wire 8, by solder or a metal clamp.

Arches 9 and 10, preferably made of sheet metal and open at the rear, are connected to 70 the strips 3 and 4 by bending their ends around said strips and riveting or otherwise securing them, said arches being made of different sizes to accommodate the varying shape of the forearm or other parts which 75 they are designed to embrace.

The arches are connected together at the front by a strip or rod 11, riveted or otherwise secured thereto, which converges toward the outer end of the splint and toward 80 the strips 3 and 4. The purpose of the arch 6 is to support the hand and its oblique inclination to adapt it to conform to the shape of the palm of the hand.

The splint on account of being constructed 85 as above described is adapted to be applied to either arm and can be made in a sufficient number of sizes to fit the different sizes of arms. To prevent undue pressure on the tissues the splint is wrapped with felt 12, 90 or other suitable material, and a strip of flexible wood 13 or other material having a pad 14 is applied to the ulnar side of the arm.

The splint and the padded strip 13 are 95 secured and held in their proper positions by means of adhesive strips or bandages 15 wound around the same.

In applying the splint, the fracture having been reduced in the usual well known 100 manner, the arm is held as nearly as possible in a fixed position, the splint bent or manipulated to conform to the shape of the palm of the hand, on the radial side in front of the thumb, the head of the radius and 105 to the upper part of the forearm, the dressing is completed by the application of a padded strip of flexible wood to the ulnar side of the arm and the splint is then secured by an adhesive strip or bandage applied around the palmar, ulnar and brachial arches. 110

We do not wish to be understood as limiting ourselves to the specific details of construction and arrangement as herein described and illustrated, as it is manifest that variations and modifications may be made in the features of constructions and arrangement in the adaptation of the device to various conditions of use without departing from the spirit and scope of our invention and improvements. We therefore reserve the right to all such variations and modifications as properly fall within the scope of our invention and the terms of the following claims.

15 What we claim is:

1. A splint provided with members converging from their inner to their outer ends and a laterally extending hand supporting member, said members so arranged as to leave a thumb opening adjacent the hand supporting member, substantially as described.

2. A splint provided with members converging from their inner to their outer ends and having an obliquely extending hand supporting member at one end, said members so arranged as to leave a thumb opening adjacent the hand supporting member, substantially as described.

3. A splint provided with longitudinal members and an obliquely extending hand supporting arch connecting said members at one end, said members so arranged as to leave a thumb opening adjacent the hand supporting arch, substantially as described.

4. A splint provided with longitudinal converging members, lateral arches and an obliquely extending hand supporting arch rigidly connected to said longitudinal members at one end, substantially as described.

5. A splint provided with longitudinal converging members, lateral arches connecting said members, means for connecting

said arches and an obliquely extending hand supporting arch rigidly connected to said converging member, substantially as described.

6. A splint provided with longitudinal members, lateral arches connecting said members and an obliquely extending hand supporting arch, said members so arranged as to leave a thumb opening adjacent the hand supporting arch, substantially as described.

7. A splint provided with longitudinal converging members, lateral arches connecting said members and an obliquely extending hand supporting arch, said members so arranged as to leave a thumb opening adjacent the hand supporting member, substantially as described.

8. A splint provided with longitudinal members, lateral arches, an outwardly converging strip connecting said arches and an obliquely extending hand supporting arch connecting said longitudinal members, said members so arranged as to leave a thumb opening adjacent the hand supporting arch, substantially as described.

9. A splint provided with longitudinal converging members, arches projecting laterally therefrom, means connecting said arches and an obliquely extending hand supporting arch connecting one end of said longitudinal members, said members so arranged as to leave a thumb opening adjacent the hand supporting arch, substantially as described.

In testimony whereof we affix our signatures in the presence of two witnesses:

NELSON W. CADY.
CHARLES B. LONGWELL.

Witnesses:

IDA NEWMAN,
GEO. W. WALTERS.
